C. T. FERNANDEZ.
COMBINED CANE AND FLAG STICK.
APPLICATION FILED MAY 24, 1915.

1,219,386.

Patented Mar. 13, 1917.

UNITED STATES PATENT OFFICE.

CHARLES T. FERNANDEZ, OF ROXBURY, MASSACHUSETTS.

COMBINED CANE AND FLAG-STICK.

1,219,386.

Specification of Letters Patent. Patented Mar. 13, 1917.

Application filed May 24, 1915. Serial No. 30,147.

To all whom it may concern:

Be it known that I, CHARLES T. FERNANDEZ, a citizen of the United States, residing at Roxbury, in the county of Suffolk and 5 State of Massachusetts, have invented new and useful Improvements in Combined Canes and Flag-Sticks, of which the following is a specification.

This invention relates to canes and more 10 particularly to combined canes and flag sticks.

The principal object of this invention is the provision of a device of this character wherein the flag or other emblem is simply 15 and efficiently arranged within the cane so that it may be withdrawn for display in parades, exercises and similar occasions.

A further object of the invention is the provision of a cane of this character having 20 a tubular sheath within which the flag may be wound and also having means for winding the flag within the sheath in either direction. Provision is also made for readily removing the flag so that various types 25 of flags may be used with one cane or old flags renewed when necessary.

Further objects of the invention will appear as the following description is read in connection with the accompanying drawing, 30 which forms a part of this application, and in which:—

Figure 1 is a perspective view of the improved combined cane and flag stick and showing the flag displayed.

Fig. 2 is a longitudinal sectional view 35 through the upper portion of the device.

Fig. 3 is a perspective view of the binding cylinder and associated locking pin.

Fig. 4 is a perspective view of the slotted 40 end of the flag cylinder.

Referring now to the drawing in detail, the numeral 1 designates the improved combined cane and flag stick as a whole which includes a cane body 2 provided at one end 45 with a reduced extension 3 received within one end of a flag cylinder 4 having extending longitudinally thereof between its ends a slot 5, said flag cylinder being connected with the extension 3 on the cane body by 50 means of a ferrule 6. The flag cylinder 4 has formed thereon adjacent its upper end a circumferentially extending bead 7 forming interiorly of the flag cylinder an annular groove 8, said upper end of the flag cylinder having formed therein at diametrically opposite points slits 9 which extend

longitudinally of the flag cylinder from the upper end to a short distance below the bead 7 and provide the flag cylinder with a plurality of spring fingers 10.

A tubular binding member 11 is arranged 60 within the flag cylinder 4, said binding member having a slot 12 extending longitudinally thereof throughout its length and provided adjacent each end with a bead 13 65 forming seats for rollers 14 and 15 having openings therein through which the respective end portions of the tubular binding member are passed, said rollers serving as bearings and spacing the tubular binding 70 member from the peripheral wall of the flag cylinder. The roller 14 which is slightly greater in diameter than the roller 15 is arranged within the flag cylinder and extends slightly within the groove 8 while 75 the portion of the tubular member which extends beyond said roller is flattened to form an operating head 16 for turning the binding member within the flag cylinder.

A locking pin 17 which is adapted to be 80 passed through a hem on a flag to be used in connection with the combined cane and flag stick is received within the tubular binding member 11 and is provided at one end with a head 18 by means of which the 85 locking pin may be withdrawn from the tubular binding member, said head also assisting in retaining the roller 15 on the binding member.

A winding key 19 which is adapted to 90 serve as a head for the combined cane and flag stick is provided with a shank 20, one end of which is adapted to be received within the upper end of the flag cylinder 4 and is provided with a slot 21 to receive the operating head 16 on the tubular binding 95 member.

The shank 20 has secured thereto a sleeve 22 which extends beyond the slotted end of the shank and is provided in its extending 100 portion with a circumferentially extending bead 23 forming interiorly of the sleeve an annular groove 24 of greater diameter and height than the bead 7 on the flag cylinder 4 and in which said bead 7 is received when 105 the winding key is operatively engaged with the tubular binding member 11 to turn the same in the flag cylinder.

When it is desired to apply a flag to the improved combined cane and flag stick as 110 shown in Fig. 1 in the drawing, the winding key 19 may be removed from the beaded

end of the flag cylinder and the binding member removed therefrom, it, of course, being understood that the slots 9 permit the fingers 10 to be moved toward each other 5 as the winding key is withdrawn from the flag cylinder and also permit the fingers to be spread apart during the passage of the roller 14 through the beaded end of the cylinder. The locking pin 17 is now withdrawn 10 from the tubular binding member 11 and passed through the hem on the flag after which the pin is again replaced in the binding member with the flag passing through the slot therein and wound about 15 the binding member after which the binding member is positioned within the flag holder.

The winding key is now connected with the beaded end of the flag cylinder and the 20 shank on the winding key engaged with the tubular binding member and if found desirable, the winding key may be turned to cause the flag to unwind from the binding member and pass through the slot 5 in the 25 flag cylinder into which it may be again drawn by rotating the winding key in the opposite direction.

Through the above described construction of the winding key and flag cylinder, 30 it will be seen that when the portion of a flag extends through the slot 5 in the flag cylinder, the winding key may be moved longitudinally of the flag cylinder to disengage the same from the operating head 35 on the binding member so that the flag may be unwound from the binding member by pulling upon the portion of the flag which extends through the slot 5.

What is claimed is:—

40 1. In a device of the class described, a cane body, a flag cylinder connected therewith and having spaced and longitudinally extending slits opening out through one end thereof, a bead on said cylinder arranged

between the ends of the slits and forming 45 an annular groove interiorly of said cylinder, a flag carrying member arranged within said cylinder and having bearing rollers thereon with one of said rollers extending slightly within said groove, and a winding key for connection with said flag carrying member engaging said bead.

2. In a device of the class described, a cane body, a flag cylinder carried thereby and having spaced and longitudinally extending slits opening out through one end thereof, a bead on said cylinder arranged between the ends of said slits, a flag carrying member within said cylinder, a winding key to be engaged with said flag carrying 60 member engaging the slotted end of the cylinder and the bead thereon, and bearing rollers on said flag carrying member for spacing the same from the inner wall of said cylinder with one of said rollers extending slightly within said bead.

3. In a device of the class described, a cane body, a flag cylinder connected with one end thereof and having spaced and longitudinally extending slits opening out through 70 one end of said cylinder, a locking bead on said cylinder arranged between the ends of said slits and forming an annular groove within said cylinder, a flag carrying member within said cylinder having bearing rollers with one of said rollers extending slightly within said groove, a winding key slidably mounted on the end of said cylinder to engage with the flag carrying member, and a bead on said winding key engageable 75 with the bead on the flag cylinder.

In testimony whereof I affix my signature in presence of two witnesses.

CHARLES T. FERNANDEZ.

Witnesses:

FRANCIS J. PERRY,
WILLIAM L. DOONAN.
